UNITED STATES PATENT OFFICE

ROBERT F. RINGLE, OF ZELIENOPLE, PENNSYLVANIA

REGULATING VALVE

Application filed July 2, 1929. Serial No. 375,558.

My invention is an improvement in regulating valves for controlling the admission and exhaust of fluid to and from the cylinder, for raising and lowering the plunger of 5 an equalizing platform of a molding machine.

In such machines the platform is elevated to receive and support the molding flask in inverted position, and to then slowly lower 10 it from the pattern, with accelerated downward movement. The operating conditions of the invention are somewhat similar to those described in patent of Ringle No. 1,452,848.

15 In the drawings showing one preferred embodiment of the invention:

Fig. 1 is a sectional view showing my improved control valve connected to the cylinder used for raising and lowering the flask 20 supporting equalizing platform;

Fig. 2 is an enlarged vertical sectional view of the valve, showing the parts in the raising position; and

25 Fig. 3 is a view similar to Fig. 2, showing the parts in the slow lowering position.

Referring to the drawings, the cylinder A contains a piston B adapted to be raised and lowered therein by the action of any suitable fluid, as oil, controlled by the valve generally 30 designated C. Piston B supports a flask supporting platform (not shown) adapted to be raised and lowered thereby in the process of lowering the flask from the pattern, in a turnover molding machine.

35 The valve C comprises an outer casing 2 and an inner valve casing 3, preferably formed integral with a cover plate 4 for closing the casing 2 and forming a fluid reservoir 5.

40 The casing 3 contains the operable parts of the entire valve, and includes a reservoir 6, having a port 7 closed by a valve 8, a port 9 closed by a valve 10 and in communication with an upper reservoir cavity 11 having an 45 outlet port 12 adapted to be normally closed

by means of a check valve 13. A pipe or conduit 14 connects the reservoir 6 with the cylinder A.

The valve 8 is provided at its upper end with a piston or plunger 15, connected thereto 50 by a threaded extension 16 and a nut 17. A spring 18 surrounds the valve guide 19 and normally maintains the valve 8 in raised position.

The valve 10 is similarly mounted, having 55 a piston member 20, an abutment or stop 21 adapted to abut against the annular edge face of valve cap 22 mounted on the cover plate 4. Spring 23 normally closes valve 10 and is provided with an adjustable screw member 60 24 mounted in the cap 22.

The valve 13 is mounted in a suitable recess in cap 13a of the casing 3, and is retained therein by a cotter pin 25. Ports 26 permit the passage of fluid from the valve seat, as 65 will be hereinafter more fully described.

An actuating fluid, such as compressed air, is introduced into an upper cavity 5a for action on the liquid in reservoir 5 by a pipe or conduit 27 from a suitable source of supply, and an independent supply of air is introduced into the chamber 22a of the cap 22 by means of a pipe or conduit 28.

The latter pipe is designated as the "fast draw line," and is provided with a three-way 75 valve 29, having an operating handle 30 and a port 31 in communication with the atmosphere. Pipe or conduit 27 is provided with a similar valve 32, having an operating handle 33 and a port 34 in communication with 80 the atmosphere.

The operation of my improved valve is as follows: To raise the plunger B, valve 32 is opened and air under pressure enters chamber 5a through conduit 27. Such pressure acting upon the oil in the reservoir raises valve 8 from its seat (Fig. 2) permitting the oil to flow under pressure by pipe 14 to cylinder A, whereby the plunger B is raised. The air pressure upon valve 13 dur. 85 96

ing this operation maintains it in a closed position.

The upward motion of the plunger B is arrested when the back pressure in cylinder A reaches a predetermined amount.

Screw member 24 may be manipulated to control the tension of spring 23, thereby determining the time of opening of the valve 10. Back pressure in chamber 6 unseats valve 10 transmitting said pressure to chamber 11, and closes valve 8 by acting upon the piston 15.

To lower the piston B, valve handle 33 is rotated to permit exhaust of the pressure in the upper portion of reservoir 5 to the atmosphere through port 34. Upon releasing such pressure, the back pressure from cylinder A will unseat the valve 13 permitting the oil from the cylinder A to return to reservoir 5 through the ports 26. Due to the comparative areas of the ports, the above process will effect a slow initial lowering of plunger B and withdrawal of the molding flask from the pattern.

When the mold flask has become disengaged from the pattern, it is desired to lower the flask more quickly. This may be done by opening valve 29, admitting air under pressure to the chamber 22a, when the pressure acts upon the piston 20, closing valve 10. The back pressure from cylinder A then acts upon the shoulder 35 of the valve 8, raising the valve and permitting the oil to return to the reservoir 5 freely and quickly.

It will be understood that the air pressure against check valve 13 is always greater than the back pressure from the cylinder, so that the plunger B may always be maintained raised by holding the air pressure in chamber 5a. When the air is released as described, then the back pressure of the fluid through port 9 unseats check valve 13, returning oil by a retarded flow to the main reservoir. By closing port 9 upon admitting pressure by pipe 28 against plunger 20, the pressure acts directly on the area of shoulder 35, lifting valve 8, for free open flow to the reservoir, resulting in more rapid lowering of the plunger.

The lowering operation is initiated by releasing air pressure on the check valve 13, for the desired reverse circulation as described.

From the foregoing description it will be seen that when it is desired to raise the plunger B rapidly, chamber 22a is opened to air pressure through pipe 28 and its valve 29 thus closing port 9 during admission of pressure through pipe 27. Also when it is desired to lower plunger B rapidly, chamber 22a is similarly opened to air pressure, closing port 9, during release of pressure through pipe 27.

On the other hand, when delayed lowering action of plunger B is desired chamber 22a

is open to the atmosphere by operation of valve 29 and port 31, opening of port 9 with admission of pressure to cavity 11, closing of valve 8, opening of check valve 13 and retarded circulation through port 26.

What I claim is:—

1. In a valve for controlling the operation of a plunger in its casing, a valve casing having a main chamber and a secondary inner chamber, a conduit connecting the secondary chamber with the plunger casing, a normally seated check valve between the main chamber and the secondary chamber, a valve controlled port between the secondary chamber and the check valve, and a plunger actuated valve subject to back pressure in the secondary chamber controlling circulation between the secondary chamber and the main chamber.

2. In a valve for controlling the operation of a plunger in its casing, a valve casing having a main chamber and a secondary inner chamber, a conduit connecting the secondary chamber with the plunger casing, a normally seated check valve between the main chamber and the secondary chamber, a valve controlled port between the secondary chamber and the check valve, a plunger and valve controlling said port, means for supplying pressure to said plunger to close the port, and a plunger actuated valve subject to back pressure in the secondary chamber controlling circulation between the secondary chamber and the main chamber.

3. In a valve for controlling the operation of a plunger in its casing, a valve casing having a main chamber and a secondary inner chamber, a conduit connecting the secondary chamber with the plunger casing, a normally seated check valve between the main chamber and the secondary chamber, a valve controlled port between the secondary chamber and the check valve, a plunger and valve controlling said port, means for supplying pressure to said plunger to close the port, a pressure spring and adjusting means therefor opposing back movement of the plunger, and a plunger actuated valve subject to back pressure in the secondary chamber controlling circulation between the secondary chamber and the main chamber.

4. In a controlling valve as described, a main liquid containing casing having an air pressure connection, an inner casing having a fluid circulating conduit, a spring retracted plunger having a valve controlling circulation from the inner casing to the main casing, a check valve subject to air pressure controlling restricted circulation between the inner casing and the main casing, and a circulation port in the inner casing between its circulating conduit and the spring retracted plunger having a controlling valve.

5. In a controlling valve as described, a main liquid containing casing having an air

- pressure connection, an inner casing having a fluid circulating conduit, a spring retracted plunger having a valve controlling circulation from the inner casing to the main casing,
5 a check valve subject to air pressure controlling restricted circulation between the inner casing and the main casing, a circulation port in the inner casing between its circulating conduit and the spring retracted plunger
10 having a controlling valve, and a pressure controlled plunger having a valve for said port.

In testimony whereof I hereunto affix my signature.

ROBERT F. RINGLE.
